(57) **CLAIM**

The ornamental design for a heel cup, as shown and described.

(51) LOC (9) Cl. **24-04**

DESCRIPTION

(52) U.S. Cl. **D24/171**

FIG. 1 is a side view of a heel cup showing my new design as it appears in use on a heel of a foot;

(58) **Field of Classification Search** D24/171,

FIG. 2 is a perspective view thereof;

D24/188, 190, 192; D2/915, 961; 36/36 R,

36/36 C, 35 R, 34 A, 34 B, 37, 173

See application file for complete search history.

FIG. 3 is a side elevational view thereof, the opposite side being a mirror image;

(56) **References Cited**

FIG. 4 is a top plan view thereof;

U.S. PATENT DOCUMENTS

FIG. 5 is an enlarged fragmental cross-sectional view taken along lines 5—5 of FIG. 4; and,

D286,948 S * 12/1986 Graham D2/961

FIG. 6 is a bottom plan view thereof.

4,762,123 A * 8/1988 Dedo 128/898

The dashed line showing of a foot in FIG. 1 is for illustrative purposes only, and is not intended to form a part of my new claimed design.
